UNITED STATES PATENT OFFICE

1,992,844

CUT-OUT FOR ELECTRIC LAMPS

Carl Severin, Cleveland Heights, and Leo R. Peters, Cleveland, Ohio, assignors to General Electric Company, a corporation of New York

Application July 23, 1931, Serial No. 552,724

3 Claims. (CL. 176—24)

Our invention relates to incandescent lamps which are to be connected in series, and more particularly to such lamps which are provided with a cut-out to prevent the electrical circuit 5 from being broken when one of the lamps in the series fails.

In certain service, several incandescent lamps are connected in series so as to use the customary electrical current available without the use of 10 a transformer or resistance. If a cut-out is not provided for each lamp, all of the lamps are extinguished upon the failure of any lamp in the series which must be located and replaced before the series will operate. This process requires 15 considerable time and effort. The use of a lamp with a cut-out is to be greatly desired as the faulty lamp will be the only lamp in the series which will be extinguished.

An object of our invention is to provide a reliable cut-out in an incandescent lamp which can be conveniently and inexpensively manufactured. According to our invention, the cut-out comprises a body of material surrounding the lead wires and attached to an insulating body through which 20 said leads pass. In the case of the ordinary Christmas tree lamp, the said insulating body is a bead of insulating material such as powdered silica which bridges both the leading-in wires. The material of the cut-out is preferably a mixture 25 of a metal powder, a finely powdered insulating material and a binder made up into a paste. Iron powder of a fineness that will pass through 100 mesh screen and which has been reduced in 30 hydrogen is preferred for the metal constituent. The binder may be sodium silicate. The insulating material may be any inert material but 35 preferably a non-hygroscopic material is used. Powdered cryolite is a desirable material as any volatilized constituents thereof would not injure 40 the lamp, but in fact might have "getter" action. Under ordinary operating conditions the sodium silicate and cryolite give the mixture insulating properties, but upon failure of the filament of a lamp in the series, the increase in voltage 45 across the lamp terminals is such that the resistance of the cut-out is not sufficient to prevent the current from passing from one lead to the other.

50 In the accompanying drawing Fig. 1 is a side

elevation of a decorative incandescent lamp embodying the cut-out of our invention; Fig. 2 is a side elevation of the bead portion of the mount on an enlarged scale and in an inverted position showing the cut-out; and Fig. 3 is a vertical section through the center of that portion of the 5 mount shown in Fig. 2.

The incandescent lamp shown in Fig. 1 comprises the bulb 10, the base 11 and the mount. The mount comprises the filament 12 having its 10 extremities attached to leading-in wires 13 and 14 which in turn are held together by the bead 15, preferably of glass. The leading-in wires connect to the shell and center contact of the base. Adhering to the bottom of the bead 15 is 15 a mass 16 of material which acts as the cut-out. The mass 16, as previously described, consists of a mixture of iron powder, cryolite powder and sodium silicate. The cut-out material in the particular form of our cut-out shown in Figs. 2 and 20 3 fills a depression 17 in the base of the bead 15 allowing the said material greater contact area 25 with the leading-in wires.

What we claim as new and desire to secure by 25 Letters Patent of the United States is:

1. In an electric lamp, the combination of a bulb, leading-in conductors extending within said bulb, an insulating body surrounding portions of 30 said leading-in conductors and supported thereby and a paste cut-out member adjacent to said insulating body and surrounding a portion of each leading-in conductor.

2. In an electric lamp, the combination of a bulb, leading-in conductors extending within said 35 bulb, an insulating bead surrounding portions of said leading-in conductors and supported thereby, and a paste cut-out member adjacent to said insulating bead and surrounding a portion of each leading-in conductor.

3. In an electric lamp, the combination of a bulb, leading-in conductors extending within said bulb, an insulating bead surrounding portions of 40 said leading-in conductors, and a paste cut-out member partially supported by said bead and surrounding a portion of each leading-in conductor.

CARL SEVERIN.

LEO R. PETERS.
